UNITED STATES PATENT OFFICE.

OLAV ESKIL JORGENSEN, OF NEW YORK, N. Y., ASSIGNOR TO WORTHINGTON PUMP AND MACHINERY CORPORATION, OF NEW YORK, N. Y., A CORPORATION OF VIRGINIA.

OIL-ENGINE SCAVENGING PUMP.

Application filed November 14, 1921. Serial No. 514,843.

To all whom it may concern:

Be it known that I, OLAV ESKIL JORGENSEN, a subject of the King of Denmark, residing at New York, county of Queens, and

5 State of New York, have invented certain new and useful Improvements in Oil-Engine Scavenging Pumps, fully described and represented in the following specification and the accompanying drawings, forming a part 10 of the same.

This invention relates to improvements in scavenging pumps for internal combustion engines and particularly for engines of the Diesel type.

15 The object of the invention is to provide a compact, rigid and durable construction which can be readily machined so as to give the required accuracy of parts, and which will permit ready and quick access to all the 20 parts for purposes of adjustment and repair.

With these general objects in view, the invention consists in the features, details of construction and combination of parts which 25 will first be described in connection with the accompanying drawings and then more particularly pointed out.

In the drawings,—

Fig. 1 is a diagrammatic end elevation, partly broken away, of a Diesel double-acting, two-cycle engine showing the new pump 30 in place thereon;

Fig. 2 is a diagrammatic side elevation of the engine with 4 engine cylinders with the new pump in place;

35 Fig. 3 is a vertical section through the center of the air-pump in a plane in which lies the main shaft of the engine;

Fig. 4 is a similar view at right angles to Fig. 3; and

40 Figs. 5, 6, 7 and 8 are horizontal sectional views on the lines 5—5; 6—6; 7—7 and 8—8 of Figs. 3 and 4.

Fig. 9 is a detail view of one of the valves, shown as a suction valve, which will be reversed for a discharge valve.

Referring to the drawings, and particularly to Figs. 1 and 2, A is a cylinder-base suitably supported on any suitable engine frame, such as is indicated at B.

50 In the particular engine construction illustrated in the drawings, each engine unit is of the double-acting, two-cycle, Diesel type, comprising a top cylinder C and a bottom cylinder C₁, these cylinders being carried by

the cylinder-base A. The engine has a main 55 crank shaft D arranged to be driven in the usual way by suitable connecting rods, not shown.

The scavenging air pump which forms the subject matter of the present invention comprises two air pumps in line with each other and having their two pistons mounted on a common piston rod, each air pump being a double-acting pump. Referring to Fig. 3, E is the cylinder of the upper air pump, and 60 E₁ the cylinder of the lower air-pump. F is the upper piston, F₁ the lower piston, and G the piston rod connected to both pistons. H is the upper cylinder head, H₁ the lower cylinder head and H₂ an intermediate head 70 common to both cylinders.

The intermediate head H₂ is flanged and is fitted into a seat formed in a septum or horizontal partition a, Fig. 4, which constitutes a part of the cylinder base A, the partition a having a horizontal flange a₁ and a vertical annular flange a₂ at the seat. The intermediate head H₂ is secured in its seat in any suitable way as, for example, by machine screws 1 which are accessible from the 75 upper side of the cylinder base when the upper air pump is removed.

The upper cylinder E is provided with a supporting member having a cylindrical hub-portion e, Fig. 4, arranged to enter a corresponding hole in the upper member or plate a₃ of the cylinder base and having a flange e₁, overhanging said plate a₃, to which it may be secured in any suitable way, as, for example, by machine screws, as indicated at 80 2, Fig. 3. The cylinder E is of such length that its lower end reaches nearly but not quite to the upper surface of the intermediate head H₂, whereby a suitable passage or 85 port for the entrance and discharge of air beneath the upper piston F is provided all around the cylinder, this opening leading into an upper chamber or space I formed in the cylinder base above the septum a. The lower cylinder is similarly constructed and 90 mounted in the cylinder base, being inserted into the cylinder base from below upward and held in place by the machine screws 3. Its upper edge extends nearly but not quite to the lower surface of the intermediate head 95 H₂, so as to leave an air passage or port all around the cylinder whereby the space in the lower cylinder above the piston F₁ is put

in communication with a lower chamber or space I_1 , Fig. 4, formed in the cylinder base below the septum a .

- The side walls of the cylinder base are provided with openings leading from the upper and lower chambers I , I_1 , respectively, to a suction valve chest K , and corresponding openings leading to a discharge valve chest K_1 . These valve chests are secured to opposite sides of the cylinder base and each has two sets of valves. The sets of suction valves are indicated at L_1 , L_2 and the sets of discharge valves at M_1 , M_2 respectively. While any suitable valves may be employed, those indicated are of the plate spring variety, for example, such as are fully disclosed in Patent No. 1,341,145, dated May 25, 1920. One advantage of such valves is that the whole valve device may be kept on the outside of the respective valve chamber and therefore is readily removable. If the valve device of Patent 1,341,145 is secured with its valve seat outward and its cap or abutment next to the wall of the valve chamber I , the valve serves as a suction valve, whereas if the seat is next to the wall of the valve chamber and the cap or abutment is outward, the valve serves as a discharge valve.
- The upper end of the cylinder E is connected by a suitable passage N with the chamber I , below the diaphragm a , the passage N opening into the top of the cylinder, as will be clear from Fig. 3. The lower end of the cylinder E_1 is connected, by a passage N_1 , with the chamber I above the diaphragm a , the passage N_1 opening into the bottom of the cylinder E_1 , as will be understood from Fig. 3. Each passage N or N_1 is formed partly in its own cylinder, and partly in the cylinder base A , as shown in Fig. 3. The part of each passage within the cylinder base is enclosed by a wall n .
- The piston rod G is reciprocated in any suitable way from the main shaft D , as, for example, through a crank O , connecting rod P , and cross-head Q running in guides R .
- The operation of the air pump is as follows: Assuming the pistons F , F_1 at the bottoms of their respective cylinders as shown in Fig. 3, it is clear that as they go upward, the air above each piston will be compressed. The air will be forced from the upper end of the cylinder E_1 directly into the space I_1 and the air from the upper end of the cylinder E will also be forced into the space I_1 through the passage N . The suction valves L_2 will close and the discharge valves M_2 will open, thus allowing the compressed air to escape to the discharge valve chest K_1 . At the same time the upward movement of the pistons F , F_1 will cause a suction beneath each piston, thereby tending to draw air into the

lower end of the cylinder E directly from the chamber I , and to draw air into the lower end of the cylinder E_1 , from the chamber I , through the passage N_1 . Hence the discharge valves M_1 will close and the suction valves L_1 will open so that the cylinders may fill with air below their respective pistons. On the reversal of the pistons, the air beneath the pistons will be driven out into the chamber I , thus closing the suction valves L_1 and opening the discharge valves M_1 . During this downward stroke of the pistons, a suction will be created above each piston, thereby drawing air from the chamber I_1 , which causes the discharge valves M_2 to close and the suction valves L_2 to open. In this way a continuous discharge of air to the discharge valve-chest K_1 takes place. From this chest the air is led by a suitable main conduit S to the scavenging air inlets of the respective engines. Each engine takes its supply from the main conduit S through a suitable elbow connection which connects the main conduit with suitable scavenging air-inlets formed in the cylinder base, one inlet for each engine.

In the preferred construction of the engine and pump, the cylinder base A is held to the frame B by long bolts which pass from the engine base through the cylinder base. Some of these bolts are indicated in cross section at b , b , Figs. 5 and 6.

It is to be understood that the pistons of the air-pump may have suitable packing rings, but as these are well known they have not been illustrated. Furthermore, any suitable means for packing the piston-rod where it passes through the lower head H_1 and the intermediate head H_2 may be employed. Conventional representations of such packing devices are indicated at g_1 and g_2 , respectively.

The construction described is particularly advantageous, because of the accessibility of the valves and the readiness with which the parts may be disassembled and reassembled. For example, by removing the respective covers of the valve chests, the valves may be reached readily and conveniently. By loosening the machine screws 2 the upper cylinder may be lifted off and access obtained to the upper piston and the packing gland carried by the intermediate head H_2 . Or by removing the machine screws 3, the lower cylinder may be let down to permit access to the lower piston. In case of necessity, the upper cylinder may be removed, then the intermediate head H_2 unfastened and lifted out through the top, together with the two pistons, by disconnecting the piston rod at the cross head.

These features are particularly important in marine engines where repairs or adjustment sometimes must be made during heavy

weather and with a pitching and rolling ship, and must be done as quickly as possible.

What is claimed is:

1. The combination with two double-acting cylinders in line with each other, a piston in each cylinder, a piston rod common to both pistons and means for reciprocating the piston rod, of a cylinder-base arranged to support both cylinders, said cylinder-base having an upper chamber in communication with the lower ends of each cylinder, and comprising passages opening at opposite sides of the cylinder-base, the cylinder-base also having a lower chamber in communication with the upper ends of both cylinders and comprising suction and discharge passages opening at opposite sides of the cylinder-base, suction valves located at one side of the cylinder base and independently controlling the suction passages to the upper and lower chambers, respectively, discharge valves located on the side of the cylinder-base opposite the suction valves and independently controlling the discharge passages of the upper and lower chambers, respectively, and valve chests secured to opposite sides of the cylinder-base and enclosing the respective valves.
2. In an air-pump, the combination, with a cylinder-base and means for supporting the same, said cylinder-base having an upper and a lower chamber separated from each other, each chamber having a suction passage and a discharge passage opening at opposite sides of the cylinder-base, valve mechanism at the outer ends of the respective passages, of valve chests secured to the cylinder-base and enclosing the respective valves, an intermediate head carried by the cylinder-base, an upper cylinder and a lower cylinder supported by the cylinder-base, heads for said cylinders, a piston rod passing through the lower head and through the intermediate head, a piston in each cylinder secured to the piston rod, the upper end of the lower cylinder being in direct communication with the lower chamber in the cylinder-base, the lower end of the upper cylinder being in direct communication with the upper chamber in the cylinder-base through a passage, part of which is formed in the wall of the upper cylinder and the remainder in the cylinder-base, the upper end of the upper cylinder being in communication with the lower chamber in the cylinder-base through a passage, part of which is formed in the wall of the lower cylinder and the remainder in the cylinder-base, and means for reciprocating the piston rod.
3. In an air-pump, the combination, with a cylinder-base and means for supporting the same, said cylinder-base having an upper and a lower chamber separated from each other, each chamber having a suction passage and a discharge passage opening at opposite sides of the cylinder-base, valve mechanism at the outer ends of the respective passages, of valve chests secured to the cylinder-base and enclosing the respective valves, an intermediate head carried by the cylinder-base, an upper cylinder and a lower cylinder supported by the cylinder-base, heads for said cylinders, a piston rod passing through the lower head and through the intermediate head, a piston in each cylinder secured to the piston rod, the upper end of the lower cylinder being in direct communication with the lower chamber in the cylinder-base, the lower end of the upper cylinder being in direct communication with the upper chamber in the cylinder-base through a passage, the lower end of the lower cylinder being in communication with the upper chamber in the cylinder-base through a passage, and means for reciprocating the piston rod.
4. In an air-pump, the combination, with a cylinder-base having an upper and a lower chamber separated by a septum having an opening, each of said chambers including a suction passage and a discharge passage, said passages opening at opposite sides of the cylinder-base, said cylinder-base also having cylinder receiving openings in its upper and lower walls, an intermediate head, removably secured in the opening in the septum of the cylinder-base and removable through the cylinder-receiving opening of the upper wall of the cylinder-base, cylinders projecting into the cylinder receiving opening of the cylinder-base and secured to the upper and lower walls thereon, respectively, suction and discharge valve mechanisms for the corresponding passages of the cylinder-base, a suction valve chest secured to one side of the cylinder-base and enclosing both suction valve mechanisms, a discharge valve chest secured to the opposite side of the cylinder-base and enclosing both discharge valve mechanisms, heads for the cylinders, a piston in each cylinder, a piston-rod extending through the lower cylinder head and through the intermediate head and carrying both pistons, and means for reciprocating the piston-rod.

In testimony whereof, I have hereunto set my hand.

OLAV ESKIL JORGENSEN.
